UNITED STATES PATENT OFFICE.

HERMAN SCHLAICH, OF LONG ISLAND CITY, NEW YORK.

RETAINING DEVICE FOR RADIATOR CAPS.

Application filed March 24, 1922. Serial No. 546,438.

To all whom it may concern:

Be it known that I, HERMAN SCHLAICH, a citizen of the United States, residing in Long Island City, county of Queens, and 5 State of New York, have invented certain new and useful Improvements in Retaining Devices for Radiator Caps, of which the following is a specification.

This invention relates to retaining devices 10 for radiator caps of automobiles and particularly for caps which are equipped with instruments such as the motor heat indicating instrument now in common use on motor vehicles. Radiator caps when so equipped, 15 offer a temptation to the petty thief, and the general object of this invention is to provide a new and improved retaining device which is simple and rugged in construction, cheap to manufacture, easily applied, 20 and when applied will be efficient for the purpose for which it is intended.

The invention will be understood from the following description, taken in connection with the accompanying drawings in which 25 Figure 1 is an elevation, partly in section, of a preferred form of the invention attached to an instrument mounted on a radiator cap, in the process of being attached to a radiator; Figure 2 is an elevation, partly in section, showing the device of Figure 1 in position after being attached to a radiator; and Figure 3 is a bottom view of the toggle member forming part of the fastening device shown in Figures 1 and 2.

30 Certain features disclosed in the present application are disclosed and claimed in my pending applications 546,437, filed March 24, 1922, for retaining device for radiator caps and Serial No. 377,501, filed April 29, 1920, 40 for retaining devices.

Referring to the drawing, the invention is shown as used in connection with a temperature indicating instrument 20 of a well known form having a threaded stem 22 45 adapted to project through a hole in a radiator cap 24 to which the instrument is secured by a nut 26 threaded upon the stem 22 and adapted to engage a washer 28 interposed between the nut and the inside of the 50 cap 24, in a well known manner. There is also shown in the drawing a portion of a radiator 30 to which is attached a neck 32 having a threaded end with which the cap 24 is adapted to engage.

55 The toggle member of the device which serves as an anchor is shown as comprising

a body portion in the form of a flat ring 40 having extending from one side thereof a plurality of lugs 41. Pivottally mounted between the lugs 41 on pins 42 are fingers 44 60 which may be of the form shown. By providing slots in the ring 40 in line with the spaces between the lugs 41, the fingers 44 may be moved to the positions shown in Figure 1; and when the toggle member is in its spread position, the fingers or arms 44 lie with their heels in engagement with the bottom of the ring 40 in the positions shown in Figures 2 and 3. As shown, the heels of the fingers 44 are provided with slots 46 70 adapted to receive an elastic band 47 which after the toggle member has been inserted through a radiator neck will assist to move the fingers 44 from the position shown in Figure 1 to that shown in Figure 2. The 75 toggle member is connected to the stem 22 of the instrument 20 by means of a chain 49 which at its upper end is attached by a swivel connection to the stem of the instrument. This swivel connection may comprise a shell 50 of the form shown having within its upper end an internally threaded ring 51 adapted to cooperate with the threaded stem 22 and be held thereon by a set screw 52 which is preferably provided 80 with a wrench socket of special form in order to render it difficult of removal. At the bottom, the shell 50 is provided with a hole through which the top link of the chain 49 may extend, thereby permitting the pin 90 54 to be passed through said link and arranged to rest on the inside of the bottom of the shell 50. The other end of the chain 49 passes freely through a hole 56 in the body portion 40 of the toggle member, and 95 a split ring 57, adapted to be passed through any link of the chain 49 and too large to pass through the hole 56 in the toggle member, may serve as an adjustable means for attaching the toggle member to the chain at 100 a proper distance from the instrument stem.

The retaining device is installed in the following manner: The inside length of the radiator neck is measured, and the effective length of the chain 49 is so adjusted that the 105 distance between the top of the toggle member and the bottom of the shell 50 will exceed the length of the radiator neck by a small amount, say one-half inch, which will permit the instrument to be tilted to the 110 position shown in Figure 2 after the retaining device is installed, which will allow

the radiator to be filled without interference by the radiator cap. The fingers 44 of the toggle member are then folded into the position shown in Figure 1 at substantially a right angle to the plane in which the fingers lie after the device is installed, against the tension of an elastic band 47, which, however, may not be necessary; and the toggle member is inserted in and dropped down through the radiator neck 32, care being taken to retain hold of the shell 50, preferably by means of a string or wire. It will be obvious that when the ends of the fingers 44 of the toggle member cease to engage the inside of the radiator neck, the fingers will move outwardly to the position shown in Figure 2 within the space in the top of the radiator. Stem 22 of the instrument may then be screwed into the ring 51 in the shell 50, and may be permanently secured in position by the set screw 52. The instrument will then be secured to the radiator by the retaining device. In some cases, instead of dropping the toggle member into the radiator before the shell 50 is attached to the instrument stem, the shell and stem may be first connected together, after which the toggle member may be dropped into the radiator neck and the fingers allowed to spread into their holding positions.

While I have shown one form in which my invention may be embodied, it is to be understood that in the appended claims I intend to cover not only this form but any other forms which embody the principles of my invention.

What I claim is:

1. A retaining device for use with a radiator cap equipped with an instrument having a threaded stem projecting through a hole in said cap, comprising a toggle member having a body portion and a plurality of automatically operable fingers movably connected thereto, and means connecting said toggle member with said instrument stem, said fingers being effective to prevent removal of the toggle member from the radiator.

2. A retaining device for use with a radiator cap equipped with an instrument having a threaded stem projecting through a hole in said cap, comprising a toggle member having a body portion and a plurality of fingers pivotally connected thereto, and means connecting said toggle member with said instrument stem, said fingers being effective to prevent removal of the toggle member from the radiator.

3. A retaining device for use with a radiator cap equipped with an instrument having a threaded stem projecting through a hole in said cap, comprising a toggle member having a body portion comprising a ring provided with a plurality of sets of lugs there being slots between each set, said slots ex-

tending thru the body part, and fingers pivotally mounted on said lugs and in said slots, and means connecting said toggle member with said instrument stem.

4. A retaining device for use with a radiator cap equipped with an instrument having a threaded stem projecting through a hole in said cap, comprising a toggle member having a body portion with a plurality of radial slots and a plurality of fingers in said slots and pivotally attached to said body portion and adapted to lie radially in substantially the same plane or be folded radially into positions at substantially right angles to said body portion, and means connecting said toggle member with said instrument stem.

5. A retaining device for use with a radiator cap equipped with an instrument having a threaded stem projecting through a hole in said cap, comprising a toggle member having a body portion, a plurality of fingers pivoted thereon, and spring means connected between said fingers for moving said fingers to extended position with reference to said body portion, and means connecting said toggle member with said instrument stem.

6. A retaining device for use with a radiator cap equipped with an instrument having a threaded stem projecting through a hole in said cap, comprising a toggle member having a body portion, a plurality of fingers movably connected thereto, and spring means for moving said fingers to their extended positions, and means connecting said toggle member with said instrument stem.

7. A retaining device for use with a radiator cap equipped with an instrument having a threaded stem projecting through a hole in said cap, comprising a connection adapted to be secured to the instrument stem, flexible means attached to said connection, and a toggle member attached to said flexible means comprising a body portion and a plurality of fingers pivotally connected thereto.

8. A retaining device for the cap of a container, said device comprising a body part, a flexible connector to connect the body part to the cap, and fingers pivoted on said body part, the length of the connector being such as to cause the cap to obstruct access to the fingers to prevent manipulation thereof and thus prevent willful removal of the retaining device.

9. A retaining device for a cap to close the neck of an automobile radiator, said device comprising a retaining element having a hole therein, a connector attached to said cap and having a loop at its lower end to extend thru the hole in said retaining element, and a split ring in said loop to hold the retaining element on the connector.

10. A retaining device for a cap to close the neck of an automobile radiator, said device comprising a retaining element, said retaining element comprising a body portion and pivoted fingers on the body portion, said fingers having slots at their inner ends, spring means to engage in said slots to swing said fingers to their effective positions, and stops to arrest said fingers in their effective positions.
11. The combination with a radiator, of a cap and instrument assembly thereon, an anchor trapped within the radiator, and means permanently connecting the anchor to the cap and instrument assembly, said anchor comprising a body portion and a plurality of fingers pivotally connected thereto.
12. The combination with a radiator of a cap and instrument assembly thereon, an anchor trapped within the radiator, and means connecting said anchor to the cap and instrument assembly, said anchor comprising a plurality of pivotally connected members collapsible for insertion into the radiator but distendible after insertion to prevent stealing of the cap and instrument assembly from the radiator.
13. The combination with a radiator, of a cap therefor, and means for securing the cap to the radiator against theft, including an anchor device comprising a plurality of pivotally connected members collapsible for insertion into a radiator and distendible after insertion to prevent removal, and means permanently connecting the cap to said anchor.
14. The combination with a radiator of a cap therefor, an anchor inescapably trapped within the radiator comprising a plurality of individual members relatively movable toward one another to diminish the breadth of the anchor for insertion into the radiator, and distendible after insertion, and means permanently connecting the anchor to the cap.

In testimony whereof I have affixed my signature to this specification.

HERMAN SCHLAICH.
